United States Patent Office

Des. 191,716
Patented Nov. 7, 1961

191,716

SPATULA OR SIMILAR ARTICLE

James L. Hyale, Chicago, Ill., assignor to Ekco Products Company, Chicago, Ill., a corporation of Delaware

Filed Dec. 19, 1960, Ser. No. 63,248

Term of patent 14 years

(Cl. D44—29)

FIG. 1 is a top plan view of a spatula or similar article showing my new design.

FIG. 2 is a side elevational view.

FIG. 3 is a bottom plan view.

FIG. 4 is a side elevational view when turned about its vertical axis through an arc of 180° relative to the position shown in FIG. 2.

FIG. 5 is an end elevational view taken on line 5—5 of FIG. 2.

FIGS. 6 and 7 are sectional views taken along lines 6—6 and 7—7 respectively of FIG. 2.

FIG. 8 is an end elevational view taken along lines 8—8 of FIG. 2.

I claim:

The ornamental design for a spatula or similar article, as shown.
